UNITED STATES PATENT OFFICE

147,489

DESIGN FOR A CHAISE LONGUE

Charles S. Cook and Earl L. Wilson, Auburn,
N. Y., assignors to Columbian Rope Company,
Auburn, N. Y., a corporation of New York

Application April 18, 1946, Serial No. 128,715

Term of patent 3½ years

(Cl. D15—11)

To all whom it may concern:

Be it known that we, Charles S. Cook and Earl L. Wilson, citizens of the United States of America, residing at Auburn, in the county of Cayuga and State of New York, have invented a new, original, and ornamental Design for Chaise Longue, of which the following is a specification, reference being had to the accompanying drawings, forming part hereof.

In the accompanying drawings the single figure is a perspective view taken from the side of a chaise longue showing our new design.

We claim:

The ornamental design for a chaise longue, as shown.

CHARLES S. COOK.
EARL L. WILSON.
